United States Patent Office.

WALTER S. MINGIS, OF NEW YORK, N. Y.

Design No. 2,538, dated January 1, 1867.

DESIGN FOR A ROUND COMB.

The Schedule referred to in these Letters Patent and making part of the same.

TO ALL WHOM IT MAY CONCERN:

Be it known that I, WALTER S. MINGIS, of the city, county, and State of New York, have invented a new Design for Round Combs, of which the following is a full, clear, and exact description, reference being had to the accompanying drawings, forming part of this specification, in which—

Figure 1 is a plan view of the upper edge of a round comb, ornamented according to my design; and

Figure 2 is a side view of the same.

A in the drawings represents a round comb, which may be made of India rubber, gutta percha, or any other material ordinarily employed therefor. Around the outside of this comb, A, from one end to the other, between the inner ends of its teeth, a, and the upper edge of the comb, I ornament the same with metallic wires or bands, b, made of an escolloped form, from one end to the other, overlapping or intersecting each other, as shown in fig. 2, which wires I secure to the comb, and, at various points of the length of the comb, ornament the same with beads or balls, C, secured thereto in any proper manner.

Having thus described my invention, I claim as new, and desire to secure by Letters Patent—

The design for ornaments for a round comb, substantially as herein described and shown in the drawings. The above specification of my invention signed by me this 19th day of November, 1866.

W. S. MINGIS.
